United States Patent

Des. 238,145
Patented Dec. 23, 1975

238,145

COMBINED BUILDING BLOCK UNIT AND CARRYING HANDLE OR SIMILAR ARTICLE

Henry King Ketcham, Geneva, Switzerland, assignor to
Rolande Ketcham, Geneva, Switzerland

Filed Apr. 26, 1973, Ser. No. 354,472

Term of patent 14 years

Int. Cl. D9—99

U.S. Cl. D9—171

FIG. 1 is a perspective view of a combined building block unit and carrying handle or similar article showing my new design;

FIG. 2 is an end elevational view;

FIG. 3 is a side elevational view, the opposite side being a mirror image of the side shown;

FIG. 4 is an end elevational view showing the end opposite that seen in FIG. 2;

FIG. 5 is a top plan view; and

FIG. 6 is a bottom plan view thereof.

I claim:

The ornamental design for a combined building block unit and carrying handle or similar article, as shown and described.
